JESSE B. STARR, OF CHANUTE, KANSAS.

CURTAIN-SUPPORT.

1,259,922.

Specification of Letters Patent. Patented Mar. 19, 1918.

Application filed February 24, 1917. Serial No. 150,700.

To all whom it may concern:

Be it known that I, JESSE B. STARR, a citizen of the United States, residing at Chanute, in the county of Neosho and State of 5 Kansas, have invented a new and useful Curtain-Support, of which the following is a specification.

This invention relates to curtain supports, and is designed more particularly to 10 be used for supporting lace curtains.

The object is to provide a device of this character which will occupy a minimum amount of space at any desired location upon a window casing, and it will support a lace 15 curtain, or other drapery, in spaced relation to the casing, independently of the window shade, so as to permit of the adjustment of the latter without interference with the curtain.

20 Another object is to provide a bracket for use in supporting lace curtains, or the like, having means for ready application to a window casing without marring the same, by dispensing with the use of screws, tacks, 25 nails, or other devices for securing the bracket in place, and which, with the aid of flexible curtain carrying means, will effectually support the curtain in spaced relation to the casing.

30 A further object is to provide a bracket which may be made of one piece of sheet metal, cut, bent, and secured in the desired shape, thus providing a device of very simple construction, capable of manufacture at 35 an extremely low cost.

A full and complete understanding of the invention will be obtained upon a consideration of the following detailed description, taken in connection with the accompanying 40 drawings forming a part of this specification; it being understood that while the drawing shows a practical form of the invention, the latter is not confined to strict conformity therewith, but may be changed or 45 modified as long as such changes or modifications mark no material departure from the salient features of the invention, as specifically pointed out in the appended claims.

In the drawings, in which like reference 50 characters designate like parts in each of the several views:

Figure 1 is a front elevation of the upper portion of a window casing having the improved curtain support in position thereon.

55 Fig. 2 is a top plan view thereof.

Fig. 3 is a perspective view, on a larger

scale than that of the preceding figures, of one form of supporting bracket.

Figs. 4 and 5 are similar views of modified forms of the bracket. 60

Fig. 6 is a plan view of a blank from which the device of Fig. 3 is formed.

Referring to the drawing, there is illustrated in Figs. 1 to 3 inclusive, a form of curtain support constructed in accordance 65 with the present invention, and which is considered to be the preferred form thereof. The device includes a pair of brackets of identical formation, which are adapted to be positioned on either side of the window casing 70 at the edges thereof and in opposed relation to each other, and to be held in such position by a connecting means consisting of an expansible coiled spring 1 extending from one bracket to the other. This coiled spring 75 1 takes the place of an ordinary curtain rod, since, in its applied position, it is stretched across the window casing 2 sufficiently tight to sustain a lace curtain or other drapery (not shown) applied thereto in any desired 80 manner.

The preferred form of the invention comprises a supporting bracket formed of a single piece of sheet metal and includes a basic portion 3, which is preferably tapered throughout the major portion of its length, and has, at its larger end, oppositely inclined margins 4. An integral face plate 5 is formed at the larger end of the bracket by bending the metal at a point intermediate 85 of its length perpendicularly to the base, thus providing rearwardly extending arms 6 which are formed as a continuation of the face plate 5, and are composed of the material of the basic portion lying outside of the 90 tapered edges 4, as shown in Fig. 6.

The basic portion, prior to bending, is slotted longitudinally of its length, along its median line, as indicated at 7. A tongue is thus provided, which, before the face plate 100 5 is formed by bending, as above described, is bent outwardly at an angle to form a brace 8, the free end of said brace being adjacent to the face plate 5. The brace 8 is preferably rounded laterally of its length 105 for the purpose of strengthening it from a point 9 where it joins with the basic member 3, adjacent to the smaller end of the latter, to a point near its outer free end from whence it continues as a reduced tongue 10. 110 The face plate 5, which tapers toward its outer end, is provided near its apex with a

slot 11 in a position to receive the tongue 10, which is passed therethrough and bent over to lie flat upon the outer face of the face plate 5, and to maintain the parts in their 5 relative positions, that is, in triangular relation.

The face plate 5 is provided at its apex, beyond the slot 11, with a terminal hook 12 having its mouth located on that side of the 10 face plate remote from the reduced end of the basic member 3, which side constitutes the outer side of the face plate in the applied position of the bracket upon the window casing 2.

15 The inwardly directed arms 6, which taper away from the base, are provided at their terminals with prongs 13 which are bent laterally to the arms 6 in a direction toward the reduced end of the basic member 3, and are adapted to be forced in between the top or side members of the window casing 2 and the wall of the room, as indicated in Fig. 2 of the drawing, or into the casing very close to the wall. The arms 20 6 are of sufficient length to permit of the proper application of the prongs 13 and are adapted to prevent any outward movement of the bracket through the action of the expanded supporting spring 1 which is provided with suitable terminal eyes to engage the hooks 12 and to exert a relatively strong pull between the brackets, toward each other. The basic member 3 is adapted to lie closely against the outer face of the top 25 member or the side of the window casing 2 and the brace 8 is adapted to prevent any bending action of the face plate 5.

The brackets, as hereinbefore described, when applied to a window casing, and having 30 the supporting spring 1 in position thereon will support a lace curtain, or other drapery of approximately the same width as the window casing.

In Fig. 4 of the drawings, there is illustrated a one piece bracket, permitting the 35 use of a shorter spring 1 and a narrower curtain than is the case in the first described form of the invention. In the latter form, a face plate 14 is provided upon the inner end of a basic member 15 and a brace 16 is integrally connected to the outer end of the basic member 15 and has a slot and tongue connection with the face plate, as indicated at 17, adjacent to a hook 18. 40

55 In this form of the invention, a single arm 19 is provided upon the smaller or outer end of the basic member 15 and is provided with similarly spaced inwardly directed prongs 20, which are adapted to perform the same 45 function as in the first described form of the invention. The brace 16 is formed in the same manner as the brace 8, by slitting the basic member.

50 In Fig. 5, another form of the invention is illustrated, in which the basic portion is

in the form of a tongue 21 struck out from the inclined brace portion 22, which latter is formed integrally with the face plate 23. A hook 24 is provided at the point of connection of the brace member 22 and face 70 plate 23, and serves the same purpose as the hooks 12 and 18. The member 21 is connected to the face plate 23 by a slot and tongue connection, indicated at 25, and the face plate 23 is or may be provided at its 75 inner portion with extensions, forming spaced legs 26 adapted to bear against the face of the window casing 2. At the point of intersection of the basic portion 21 and the brace 22, the bracket is provided with a 80 rearwardly extending arm 27 similar to the arms 6 and 19, and having inwardly directed, spaced prongs 28, which like the prongs 13 and 20, are adapted to engage behind the rear faces of the outer edges of 85 the window casing 2.

In all three forms of the invention, the hooks for receiving the supporting spring 1 are spaced away from the outer face of the window casing 2 a sufficient distance to hold 90 the spring out of the path of movement of a shade roller (not shown) which might be applied to the window casing 2. Thus, an ordinary window shade may be provided without interference with a lace curtain or 95 other drapery supported by the device of the present invention.

From the foregoing, it will be seen that an extremely simple bracket for maintaining a flexible lace curtain support in position upon a window casing has been devised, and that the same, by reason of its one piece structure, is susceptible of manufacture at an extremely low cost, and may be easily applied to or detached from a window 100 casing without marring the same.

What is claimed is:

1. A bracket of the character described, comprising a blank having a major axis slit longitudinally at its center for a portion of the length thereof, and bent to provide portions extending at an angle to each other, the part intermediate the slits bent to provide a brace connecting said portions to constitute a triangular-shaped frame, said blank being formed with a portion for biting engagement with a window frame, and a resilient curtain suspension member connected with the other portion. 110

2. A bracket of the character described, comprising a blank having a portion tapered in one direction and its remaining portion tapered in the reverse direction, the major portion being formed with slits converging in the direction of the reversely 125 tapered portion, a brace cut from the blank longitudinally and centrally thereof, the blank being folded transversely at the inner ends of said slits to provide a base throughout the major portion at substantially right 130

angles to the latter portion forming a face plate with arms at opposite sides thereof constituting continuations of said face plate, the brace being connected to the face plate 5 and extending at an angle from the base, a hook formed at the smaller end of the face plate, and prongs at the free ends of said arms.

In testimony, that I claim the foregoing as my own, I have hereto affixed my signature in the presence of two witnesses.

JESSE B. STARR.
